UNITED STATES PATENT OFFICE.

ALBERT B. SOLINGER, OF SACKETT, PENNSYLVANIA.

COUPLING FOR OIL-WELLS.

1,138,421.

Specification of Letters Patent.

Patented May 4, 1915.

Application filed August 28, 1914. Serial No. 859,079.

To all whom it may concern:

Be it known that I, ALBERT B. SOLINGER, a citizen of the United States, residing at Sackett, in the county of Elk and State of Pennsylvania, have invented certain new and useful Improvements in Couplings for Oil-
5 Wells; and I do hereby declare the following to be a full, clear, and exact description of the invention, such as will enable others skilled in the art to which it appertains to
10 make and use the same.

My invention relates to new and useful improvements in coupling apparatus for oil and other wells and resides in the provision
15 of a simple and effective coupling member that will serve to couple the stand pipe with the well tubing of a well and suspend the tubing from the well casing at the upper part of the well in such manner that the
20 tubing will not become detached from the coupling member from shocks or jars or from heat caused by fire.

Another object is to provide a coupling member of the character described that may
25 be easily and readily put into position and which is simple as to construction and inexpensive to manufacture.

Another object is to generally improve coupling members of the character described
30 so as to render them more practical, reliable and efficient in operation and more durable and commercially desirable.

The above and additional objects are accomplished by such means as are illustrated
35 in the accompanying drawings, described in the following specification and then more particularly pointed out in the claims.

With reference to the drawings, wherein I have illustrated the preferred embodiment
40 of my invention as it is reduced to practice, and throughout the several views of which similar reference numerals designate corresponding parts.

Figure 1 is a detail side elevation of the
45 coupling member removed from the casing. Fig. 2 is a fragmentary vertical sectional view taken through a well showing the coupling members in position.

Referring to the drawings by characters
50 of reference, the numeral 1 designates as an entirety the platform of the well, 2 the well casing mounted on the platform, and 3 a collar threaded upon the upper end of the casing 2 exteriorly thereof.

55 My improved coupling member designated 4 as an entirety serves to connect the well

tubing 5 with a vertical stand pipe 6. A discharge pipe 7 is connected with the stand pipe 6 and extends outwardly therefrom at right angles thereto.

My improved coupling 4 comprises a tubular body portion 8 that is formed intermediate its ends with an annular flange 9. The flange 9 is provided upon its lower face and the periphery thereof with a depending marginal flange 10 that is designed to seat within an annular groove 11 formed in the upper face of a supporting ring 12. The supporting ring 12 is positioned within a recess 13 formed in the upper part of the collar 3 on the upper end of the casing 2 and rests upon the upper end of the casing 2 as well as the collar 3. The supporting ring 12 snugly fits the tubular body 8 of the coupling member 4. The ends of the coupling member 4 interiorly thereof are screw threaded as at 14 and receive the externally screw threaded ends of the tubing and stand pipes 5 and 6 respectively. The usual plunger rod 15 is mounted within the tubing, 80 coupling member and stand pipes.

With my improved coupling member it will be readily seen that the stand pipe and tubing may be coupled in such manner that derangement of the tubing relative to the coupling member and stand pipe is prevented. The interior connection of the tubing with the coupling member insures the holding of the tubing in case of fire since the heat will not affect the threads so as to cause 90 the tubing to drop from the coupling member.

The device may be readily assembled and as easily disassembled for shipment or storage but serves principally to expedite the 95 setting up of well structures.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as set forth.

What is claimed is:—

1. A coupling member for oil wells consisting of a tubular body portion, an annular

flange formed intermediate the ends of the body portion, a depending marginal flange on the under face of said annular flange and a ring having an annular groove in its upper 5 face to be mounted upon the upper part of the well structure and receiving the depending flange in the groove thereof.

2. The combination with a well casing, stand pipe and well tubing of a coupling 10 member for the tubing and stand pipe consisting of a tubular body portion having internal screw threads at its ends receiving the adjacent ends of the stand pipe and well tubing, an annular flange formed integral

with the coupling member intermediate the 15 ends thereof and having formed integral therewith on its under face a depending marginal flange, a ring mounted upon the casing and having an annular groove in its upper face to receive the depending marginal flange.

In testimony whereof I affix my signature in presence of two witnesses.

ALBERT B. SOLINGER.
